UNITED STATES PATENT OFFICE

161,866

COMBINATION FISHERMAN'S CREEL AND
TACKLE BOX

Milton H. Peterson, Midland, Mich.

Application May 27, 1950, Serial No. 10,251

Term of patent 14 years

(Cl. D31—4)

To all whom it may concern:

Be it known that I, Milton H. Peterson, a citizen of the United States of America, residing at Midland, Midland County, Michigan, have invented a new, original, and ornamental Design for a Combination Fisherman's Creel and Tackle Box, of which the following is a specification, reference being had to the accompanying drawing, forming part thereof.

In the drawing:

Fig. 1 is a perspective view of a combination fisherman's creel and tackle box, showing my new design, with the large lid open.

Fig. 2 is another perspective, with the large lid closed and the small lids open.

Fig. 3 is a plan view, all lids being closed.

Fig. 4 is a front elevation of the closed box.

Fig. 5 is a side elevation of the closed box, and

Fig. 6 is a bottom view of the box.

The essential features of my design reside in the portions shown in full lines.

I claim as my invention:

The ornamental design for a combination fisherman's creel and tackle box, substantially as shown and described.

MILTON H. PETERSON.
